(57) **CLAIM**

The ornamental design for an ornament holder as shown and described.

DESCRIPTION

FIG. 1 is a perspective view of an ornament holder.

FIG. 2 is a front view thereof.

FIG. 3 is a right side view thereof.

FIG. 4 is a left side view thereof.

FIG. 5 is a top view thereof.

FIG. 6 is a bottom view thereof; and,

FIG. 7 is a perspective view thereof, shown in a state of use. The broken lines shown in FIG. 7 illustrate environmental structure and form no part of the claimed design.
